[57] CLAIM

The ornamental design for a range hood, as shown and described.

DESCRIPTION

FIG. 1 is a perspective view of a range hood incorporating my design, viewed from the upper right;

FIG. 2 is a top view of the range hood;

FIG. 3 is a bottom view of the range hood;

FIG. 4 is a front view of the range hood;

FIG. 5 is a rear view of the range hood; and,

FIG. 6 is a right hand side view of the range hood, the left hand side view being substantially a mirror image thereof.

The broken line showing of environmental structure in FIGS. 1-6 is for illustrative purposes only and forms no part of the claimed design.
